UNITED STATES PATENT OFFICE.

EMIL ULLMANN, OF BERLIN, GERMANY, ASSIGNOR TO THE FIRM OF ORENSTEIN & KOPPEL-ARTHUR KOPPEL AKTIENGESELLSCHAFT, OF BERLIN, GERMANY.

BUFFER-COUPING FOR RAILROAD-VEHICLES.

1,091,547.

Specification of Letters Patent. Patented Mar. 31, 1914.

Application filed October 30, 1912. Serial No. 728,664.

To all whom it may concern:

Be it known that I, EMIL ULLMANN, a subject of the German Emperor, residing at 20 Landgrafstrasse, Berlin, Germany, have invented certain new and useful Improvements in Buffer-Couplings for Railroad-Vehicles, of which the following is a specification.

The present invention relates to improvements in so-called buffer-couplings, namely 10 such coupling devices which at the same time serve as buffers, as they are frequently used, in particular on the cars running on narrow gage lines.

The present invention consists in the peculiar construction of the buffer-heads and of the members effecting the coupling, besides the peculiar combination of these various parts, as shall be hereinafter described and covered in the claims.

20. In the accompanying drawings the present invention is exemplified in a constructional form.

In these drawings Figure 1 is a longitudinal, vertical section through the buffer-coupling of a car. Fig. 2 is an elevation partly in section, and Fig. 3 is a front view. Fig. 4 is a longitudinal vertical section through the front parts of the two buffer-couplings of two cars standing opposite to each other, 30 showing the coaction of the coupling members.

In Figs. 1 and 2 the numeral 1 indicates the end sill, which consists of a channel iron secured to the respective end of the car. To 35 this channel iron is bolted a yoke-shaped part 2, which serves as a guide for the buffer 3. The inner end of this buffer is reduced at 4 and passes through the bore of a cap 5, which is guided within the yoke-shaped part 2 to be capable of longitudinal displacement therein during the outward pull of the buffer 3. Normally the cap 5 rests against the sill 1. This bore in the cap 5 forms the second 45 guide for the buffer 3, which is held in normal position by means of a spring 6. The play of the buffer toward outside is limited by means of a nut 7 screwed on the end 4 of the buffer.

The buffer 3 terminates at its front end in 50 form of a fork-like member 8 the branches of which are flanged over in front both upward and downward. To these flanges is secured the buffer-head 9 which consists of a wrought-iron cap which has a horizontal slot 55 10 extending across its whole width. In the

top and bottom wall of this cap are bores 11, 11 concentrical to each other. Coaxially to these bores 11 are two bores 12, 12 in the branches of the forked member 8. All bores are essentially of the same diameter. Into 60 these bores the coupling pin 13 is fitted, which consists of a shank of a uniform diameter and a head composed of a shoulder 14 and a ring 15 for facilitating its manipulation. Over the pin 13 is fitted a washer 16 65 which lies in the bifurcated mouth 10 of the buffer-head on the lower branch of the fork 8. The lower end of the pin 13 has two longitudinal grooves 17, 17 which are closed at the extreme end by means of a screw cap 18 70 having substantially the same diameter as the pin. The bore of the washer 16 corresponds in its form with the form of the section of the lower end of the pin.

Each car is fitted at each end with a coupling and buffer device of the hereinbefore described character. On the coupling pin 13 of each buffer-head hangs a coupling member 19 having the form of a chain-link.

For coupling two cars the latter are moved 80 with their coupling heads opposite to each other as shown in Fig. 4. The pin 13 of the one car is then lifted, see Fig. 4 on the right hand; while being lifted it will rise in the bore of the washer and raise the latter only 85 after the noses in the bore of the washer, corresponding to the grooves 17 in the pin bear against the cap 18 at the lower end of the pin. When the pin is then lifted still 90 farther, the respective coupling member 19 90 will likewise be raised by the washer. Now the coupling member of the other car can be introduced; if necessary from the side, into the mouth of the buffer-head and beneath the lifted coupling pin. When the latter is then 95 again lowered, the two cars will be coupled together.

The arrangement of the cap 5 enables the rear end of the buffer shank to enter into this cap, thus a buffer shank hole in the truck 100 frame being dispensed with.

The raising of the washer by the lifting coupling pin may of course also be obtained in any other manner than the one described. The hereinbefore described constructional form is, however, preferable, as it allows of employing a uniform diameter of the coupling pin and therefore a secure support of the same in bores of uniform diameters. The improved buffer-coupling ac- 110

cording to the present invention may furthermore also be employed on any other kind of vehicles.

What I claim is.

- 5 1. Combined buffer and coupling device for railroad-vehicles fitted at the frame of the vehicle, the front end of the buffer having the form of a fork with horizontally extending branches, said branches carrying a
- 10 cap having a horizontal mouth on its front side, the rims of said cap and the two branches of the said fork having bores in the same vertical axis, a coupling pin in said bores, and means securing said pin against bores, and means securing said pin against removal from said buffer when in unlocking position.
- 15 2. Combined buffer and coupling device for railroad-vehicles fitted at the frame of

the vehicle, the front end of the buffer having the form of a fork with horizontally extending branches, said branches carrying a cap having a horizontal mouth on its front side, the rims of said cap extending rearward, the upper and the lower rim of said cap and the two branches of the said fork having bores in the same vertical axis, a coupling pin in said bores, and means securing said pin against removal from said buffer when in unlocking position.

In testimony whereof I affix my signature 30 in presence of two witnesses.

• EMIL ULLMANN.
